MULTISTAGE INCINERATOR FOR DRYING
AND BURNING WET REFUSE

James G. Ames, Aurora, Ill.

Application July 26, 1945, Serial No. 607,181

11 Claims. (Cl. 110—18)

1

This invention relates, in general, to the art of incineration, and has particular relation to an improved incinerator for the disposal of garbage, rubbish, and other refuse or waste material.

While the embodiment of the invention which I shall describe hereinafter in connection with the drawings is a gas-fired device particularly adapted for domestic use, it is to be understood that the invention in its broader aspects is not limited to such use but may be employed elsewhere as suitable and desired.

In the conventional incineration process a high temperature flame is made to impinge directly on a mass of wet or damp garbage. The result is scorching, which produces offensive odors, along with a heavy smoke, which have a tendency to leak out of the incinerator because of lack of sufficient draft. This lack of draft is due to the lack of high temperature, the heat of the burner flame being rapidly absorbed by the water or moisture content in the refuse.

The present invention may be characterized as an improvement in incinerator, in general, of the type disclosed and claimed in my copending application, Serial No. 607,180, filed July 26, 1945. In such type of incinerator, the refuse is disposed of by multi-stage incineration, having a first stage in which the garbage or other refuse is dried or dehydrated (completely or partially) at a relatively low temperature and preferably without direct impingement of the flame on the refuse—for example, by relatively low temperature flue gasses—and a second or ignition stage in which a hot flame impinges on the dried or dehydrated mass to burn and thereby dispose of same.

As a result of first drying or dehydrating the garbage or other refuse before igniting or burning the same, smoke and odor are very greatly reduced; carbon deposits and the resulting chimney fires are avoided, and the amount of resulting ash is reduced. Moreover, the very hot ignition flame assures a strong draft, even on hot, humid days, which draft effectively carries away any small amount of smoke or odor high enough above the chimney to give good dispersion. The strong draft induced by the hot flame also seems to eliminate the pressure zone in the combustion chamber, which, in turn, solves the problem of smoke, for example, in the basement.

One of the main objects of the present invention is to provide an improved multi-stage incinerator in which separate drying or dehydrating and ignition or burning chambers are provided, one for the drying or dehydrating stage and the other for the ignition or burning stage.

Another object of the invention is to provide in conjunction with the improved multi-stage incinerator of the character described, an improved air control in which the air for drying or

2

dehydrating and for ignition or burning of the garbage or other refuse is compelled to pass first through the drying or dehydrating chamber, and from the drying or dehydrating chamber into the ignition or burning chamber and thence out, for example, through the flue.

The improved method of air control of the present invention enables multi-stage incineration in a plurality of compartments, as distinguished from multi-stage incineration in one compartment where it is necessary to subject the refuse to the first stage and thereafter to the second stage, and to complete the second stage of incineration before again subjecting further refuse to the first stage of the process. The multi-compartment feature of the multi-stage incineration process of the present invention enables subjecting the dried or dehydrated refuse to the second stage of the process in one compartment, and, simultaneously or without completing the second stage in such compartment, to subject further refuse to the first stage of the process in another compartment. This is highly advantageous.

Another object of the invention is to provide an improved multi-stage incinerator of the character described having a hearth plate or refuse support for receiving and supporting the garbage or other refuse upon introduction of same into the incinerator, and in which the refuse is subjected while in position on said hearth or refuse support, first, to a drying or dehydrating stage, and thereafter, and with the dried or dehydrated refuse remaining in position on said support, subjecting it to an ignition or burning stage to burn and dispose of the same.

Another object of the invention is to provide improved means which is operable upon completion of the drying or dehydrating stage to move the dried or dehydrated garbage or other refuse to ignition or burning position.

Another object of the invention is to provide an improved drying and igniting burner arrangement.

Another object of the invention is to provide for relative movement between the drying and ignition chambers, or between the separated masses of garbage or refuse for drying and for ignition and the drying and igniting burner arrangement for the purpose of accomplishing with the improved air control and separation of the masses of refuse multi-stage incineration in the manner set forth.

Another object of the invention is to provide an improved form of hearth or refuse support for supporting the garbage or other refuse in the drying or dehydrating stage and in the ignition or burning stage, which hearth or refuse support is of a character or provided with cooperating

means for controlling the admission of air for circulation, as described.

Another object of the invention is to provide in an improved multi-stage incinerator of the character described a pair of separate chambers each of which serves at one time as a drying or dehydrating chamber and, at another time, as an ignition or burning chamber.

Another object of the invention is to provide, in conjunction with the multi-stage incinerator in which there are a pair of separate chambers each of which serves at one time as a drying or dehydrating chamber and, at another time, as an ignition or burning chamber, improved flue means operable to open at one time from one chamber and, at another time, from the other chamber.

Another object of the present invention is to provide an incinerator of the class described having various features of novelty and advantages, and which is particularly characterized by its simplicity and compactness in construction, its economy in manufacture, its effectiveness in use, and its ability to dispose of the garbage or other refuse more completely and economically and with less offensive odors and smoke.

Further objects and advantages of the invention will appear from the following detailed description, taken in connection with the accompanying drawings which illustrate the method of constructing and operating one form of device embodying the present invention.

In the drawings:

Figure 1 is a vertical sectional view of one form of incinerator embodying the present invention;

Figure 2 is a top plan view of the incinerator shown in Figure 1;

Figure 3 is a horizontal sectional view taken along the line 3—3 of Figure 1;

Figure 4 is a horizontal sectional view taken along the line 4—4 of Figure 1;

Figure 5 is a fragmentary horizontal sectional view showing a modified form of device provided with means for tearing, pulling apart or mutilating the garbage or refuse;

Figure 6 is a vertical sectional view of a modified form of incinerator embodying the present invention;

Figure 7 is a horizontal sectional view taken along the line 7—7 of Figure 6;

Figure 8 is a horizontal sectional view taken along the line 8—8 of Figure 6; and

Figure 9 is a horizontal sectional view taken along the line 9—9 of Figure 6.

Referring first to the embodiment of the invention illustrated in Figures 1, 2, 3, and 4, I have shown in these figures, for purposes of illustration, an incinerator having an upright outer side wall 10 formed, for example, of sheet metal and of cylindrical or other suitable form. The top is closed, except for a flue outlet to be presently referred to, by a top wall 11, and the bottom is closed by a bottom wall 12. A removable ash receiving receptacle 13 is shown as resting on the bottom 12. A handle 14 is provided on the front of the receptacle 13 for removing same to empty any ashes which, with the present invention, are reduced to a minimum.

The hearth plate, grate or refuse support 15 is supported, for example, in fixed position within the incinerator by brackets 16. An upright shaft or post 17 extends vertically through the space above the grate 15 and is journaled to turn at 18

in the grate 15 and, at 19, in the top wall 11. The upper end of the shaft or post 17 extends upwardly above the top wall 11 for a purpose which will be presently described.

5 The two chambers 20 and 21 of the device are defined by semi-cylindrical walls 22 and 23 respectively, formed, for example, of sheet metal and disposed concentrically within and spaced inwardly at 24' from the outer wall 10. The ends of the semi-cylindrical walls 22 and 23 terminate in integral diametrically extending walls 24 and 25 which provide diametrically across the space above the grate 15 a wall or partition 24, 25 of double thickness. This double thickness wall or partition 24, 25 is fixed at 26 to turn with the shaft or post 17 in turning the post to move the garbage or other refuse from drying or dehydrating position to ignition or burning position. The hearth plate or grate 15 may, within the broader aspects of the invention and with modification, be arranged to turn with the wall or partition 24, 25 and semi-cylindrical walls 22 and 23, instead of being fixed in place as described. The inner surface of the outer wall 10 may be lined with asbestos or other insulating material (not shown) which, where employed, is preferably spaced from the walls 22 and 23 to provide an annular space between the wall 10 and walls 22 and 23.

20 The walls 22 and 23 preferably terminate at a distance beneath the top wall 11, and the walls 24, 25 are cut away or terminate at a sufficiently greater distance below the top wall 11 to provide spaces 28 through which the air and gases of combustion pass from the drying chamber 21 as the device is shown in Figure 1, into the ignition or burning chamber 20, and thence out through the flue 29. The top wall 11 is provided at the top of the drying or dehydrating chamber 21 with a cover 30 hinged, for example, at 31, and provided with a handle 32 for raising the cover 30 to open position for the introduction of the garbage or other refuse into the drying or dehydrating chamber 21. Rods 34 are shown extending in parallel relation across the bottom of the drying and ignition chambers 20 and 21, and anchored at their ends in walls 22, 23 for supporting any bulky and heavy masses of garbage or other refuse above the grate 15. This, of course, may vary. The bottom of the incinerator may be supported on legs 36, although this, too, may vary.

25 The drying and ignition burner arrangement is shown as comprising a suitable gas or fluid fuel burner 40 underlying the grate 15; the particular burner illustrated in the drawings having a plurality of burner outlets 41. A gas or fuel supply pipe 42 extends from outside the incinerator through the wall 10 and is connected to the burner 40 for supplying fuel to the burner from a suitable source of supply. A shield 43, illustrated in the form of a metallic plate of slightly angular form, is suspended, for example, by supports 44 from the bottom of the grate 15 in position spaced above the burner 40 to protect the garbage or other refuse in drying chamber 21 from direct impingement of the flame 45 thereon through the openings in the adjacent portion of the grate 15.

30 The ignition burner of the drying and ignition burner arrangement comprises a fuel supply tube 48 connected at 49 to the fuel supply pipe for the drying burner 40. The tube 48 extends into the incinerator through the wall 10, and its inner end is turned at right angles and provided with

a fuel outlet tip 50 directed across the drying flame 45 above the burner 40. The tube 48 is provided, for example, with a push button or flash valve 55 for establishing an ignition flame. An open-ended flash tube 52 is suspended, for example, by a support 53 from the bottom of the grate 15. The tube 52 has one end in alignment with the outlet tip 50, and may be inclined slightly toward the opposite end to direct the ignition flame over a portion of the bottom of the grate 15, as shown in dotted lines at 56 in Figure 1 when the push button of the valve 55 is depressed to ignite the dried or dehydrated refuse in the ignition or burning compartment or chamber 20. The tube 52 illustrated in the drawings is of generally square or polygonal cross section, and has a longitudinal slot or opening 58 along one of the upper corners thereof for admitting air to maintain the ignition flame as it is flashed through the tube.

The hearth or grate 15 has, along the side above the burner 40 where the drying or dehydrating stage takes place, a plurality of suitable openings or apertures 60 for circulation of the heated air into the drying chamber at the location 21, as shown in Figure 1. The opposite side of the grate 15 has, along the portion beneath which the ignition flame 56 plays when projected from the tube 52, a plurality of openings 62 through which the ignition flame 56 is adapted to impinge on the dried or dehydrated garbage or other refuse to ignite the same so that it will be burned and thereby disposed of.

For the purpose of rotating or turning the post or shaft 17 and the partition 24, 25 carried thereby, with its open-ended semi-circular walls 22, 23, the upper projecting end of the shaft 17 is provided with a handle 65 pivoted at 66 to a suitable fitting on the upper end of the shaft 17. The top wall 11 of the incinerator has a stop 68 which extends upwardly from the wall 11 and, by cooperation with the handle 65, limits turning movement or rotation of the handle 65 in a counterclockwise direction (Figure 2) at the position shown in full lines in Figure 2. The handle 65 is adapted to be swung about the horizontal axis of the pivot 66 to the dotted line position shown in Figure 2, and then turned through 180° from its dotted line position to its full line position to turn the compartment 21 and the dried or dehydrated garbage or refuse therein from drying or dehydrating position, as shown in Figure 1, to igniting or burning position, in which compartment 20 is illustrated in Figure 1. In this way, full 360° rotation of the handle 65, which would be prevented by the flue 29, is unnecessary.

In disposing of garbage or other refuse in accordance with the embodiment of the invention illustrated in Figures 1, 2, 3, and 4, the following sequence is followed:

The cover 30 is opened and the garbage or other refuse, in wet or moist condition, is introduced into the incinerator chamber 21 into position on the grate 15 and rods 34. With the burner 40 ignited, the heated air passes up through the openings 60 in the grate 15, thereby subjecting the wet or moist refuse to a drying or dehydrating stage at a relatively low temperature and preferably without direct impingement of the flame 45 on the refuse. The heated air and products of combustion pass up through the chamber located in the position as shown at 21 and through openings 28 into the ignition chamber located as shown at 20 in Figure 1, and out through the flue 29.

The grate openings 62, beneath the ignition or firing position 20 as shown in Figure 1, are restricted relative to the openings 60 so that there is no appreciable or at least no objectionable bypassing of the heated air through the ignition chamber, as located at 20, to the flue 29. In this way a novel and important air control is provided whereby the air for drying or dehydrating and for firing or burning of the refuse is compelled to pass, first, through the chamber in drying or dehydrating position, as indicated at 21, and from the drying or dehydrating position into the chamber in ignition or firing position as indicated at 20, and thence out through the flue 29.

15 In the drying or dehydrating stage of the process, the moisture content of the refuse is distilled off or expelled and, as a result, the refuse is dried or dehydrated without scorching and without objectionable smoke or offensive odors.

20 Where I refer herein and in the claims to drying or dehydrating the refuse, I intend to cover either complete or partial drying or dehydration of the material.

When the drying or dehydrating stage is completed by distilling off or expelling the moisture (garbage averages about 95% moisture), the handle 65 is manipulated to rotate the partition 24, 25 through 180°, moving the compartment, shown in drying position at 21 in Figure 1, and the dried or dehydrated garbage or refuse with it to the position occupied by the compartment 20, as the device is illustrated in Figure 1. With the dried or dehydrated garbage or other refuse in the position occupied by the compartment 20 in Figure 1, the igniter valve button 55 is depressed to project the ignition or firing flame 56 which impinges through the relatively restricted openings 62 in the grate 15 directly on the dried or dehydrated mass of refuse to burn and dispose of same without objectionable smoke or offensive odors. Combustion of the dried or dehydrated refuse in the ignition or firing stage is fast, being usually completed in a few minutes.

In carrying out the invention, the previously dried or dehydrated refuse is extremely combustible at the ignition stage of the process. The result is a fast burning, hot flame which thoroughly consumes everything combustible, leaving only a surprisingly small amount of fine ashes. The very hot flame assures a strong draft even on hot, humid days, which carries any small amount of smoke or odor high enough above the chimney to give good dispersion. The strong draft induced by the hot fire in the firing stage of the process seems to eliminate any pressure zone in the combustion chamber, which, in turn, solves the problem of smoke in the basement. Moreover, as already pointed out, smoke and odor are very greatly reduced, and the two stage incineration according to the present invention seems noticeably to reduce the amount of ashes resulting.

It will be noted that the compartment located in the position indicated at 21 in Figure 1 serves in this position as the drying or dehydrating compartment, and when this same compartment is turned 180° to occupy the position occupied by the compartment 20, as illustrated in Figure 1, it serves as the ignition or firing compartment of the device. With the plural and, more specifically, two-chamber or compartment form of device as shown and described, garbage or other refuse may be introduced into the compartment located as shown at 21 on one side, while the ignition or firing stage is taking place on the opposite side,

i. e., in the compartment located at the position indicated at 20 in Figure 1.

In the embodiment of the invention shown fragmentarily in Figure 5, the partition 24', 25' corresponds to the partition 24, 25 of the preceding embodiment of the invention. In this case the semi-circular walls 22, 23 carried by the partition of Figure 1 are omitted, and the wall 10' has inwardly extending pins 65 or the like for tearing, pulling apart, or mutilating the dried or dehydrated mass of refuse as it is moved from drying position to firing or ignition position by 180° rotation of the partition 24', 25'. The openings 60' in the grate 15' are shown in this case of annular elongated form.

In the embodiment of the invention illustrated in Figures 6, 7, 8, and 9, the incinerator has the outer upright side wall 70, diametrically disposed partition 71, 72, and grate 73 which are similar to the corresponding parts in the preceding embodiment of the invention except that the openings in the grate 73 are different, as will be described presently, and the semi-circular walls carried by the partition 71, 72 and operable within the wall 70 are omitted. These semi-cylindrical walls may, of course, be employed in this form of the invention if desired; the showing being more or less diagrammatic for purposes of illustrating this form of the invention. The removable ash-receiving receptacle 74 is shown resting on the bottom 12' with an inclined marginal plate 75 for directing the ashes into the receptacle.

In this form of the invention the upright axial post or shaft 76 is journaled to turn at 77 in the grate 73 at the axis thereof, and, at 78, to turn in a spider 79 mounted in the flue 80. The partition 71, 72 in this embodiment of the invention is positioned in fixed position instead of being mounted to turn with the shaft 76 as in the embodiment of the invention illustrated in Figures 1 through 4. The flue 80, instead of opening only from one chamber or compartment, opens from both compartments, and a damper 81 is fixed to turn with the shaft 76 and operates alternately to close the openings from the respective chambers to the flue 80 as the chambers alternately operate or function as drying or dehydrating and as ignition or firing chambers. The top of each chamber 82 and 83 is provided with a cover 84 hinged at 85 and having a handle 86 for raising the cover to open position for the introduction of garbage or other refuse into the respective chambers at such time that the chambers are functioning as drying or dehydrating chambers, as will presently appear. If desired, interlock means may be provided for preventing opening of the covers 84 at such time that the chambers 82 or 83 are functioning as ignition or firing chambers.

The drying and ignition or firing burner arrangement in this form of the invention comprises a drying burner 90 and an ignition or firing burner 91. The drying and ignition or firing burners 90 and 91 are joined together into a unitary assembly, for example, by bolts 92 or the like, and this burner assembly 90, 91 is mounted at 93 on the lower end of the shaft 76 to turn with the shaft 76 and partition 71, 72 upon rotation thereof. The drying burner 90 has an overlying shield 94 for protecting the garbage or other refuse on the grate 73 in position above the drying burner 90 from direct impingement of the drying burner flame 95 thereon through the grate openings 96.

The ignition or firing burner 91 has, for ex-

ample, an upwardly directed outlet for projecting the ignition or firing flame through an opening 97 in a shield 98 for direct impingement through the grate openings 99 with the dried or dehydrated refuse in position above the ignition or firing burner 91. The shield 98 is mounted on the lower end of the shaft 76 to turn as a unit with the shaft 76, burners 90, 91, partition 71, 72, and damper 81. Due to the presence of the shield or plate 98, which restricts the grate openings 99 in firing or ignition position, these openings 99 may be substantially the same size and arranged substantially the same as the grate openings 96. For the purpose of rotating the shaft 76, partitions 71, 72, burners 90, 91, damper 81, and shield or plate 98 through 180°, the shield or plate 98 has a handle 100 which extends out through a circumferential slot 102. The slot 102 extends circumferentially about the wall 70 a sufficient extent to permit the desired 180° rotation of the parts described.

A gas or fuel supply pipe 103 is connected to supply fuel to the drying burner 90, for example, through a spud 104. A second fuel supply pipe 105 is connected to supply fuel to the ignition or firing burner 91, for example, through a spud 106. The pipes 103 and 105 may be fixed in position because the inlets to the respective burners 90 and 91 are coaxial with and turn about the spuds 104 and 106. The pipe 103 may be provided with a suitable control valve (not shown), and the pipe 105 is provided with a suitable valve—such as a push button flash valve—(not shown) for projecting the igniting or firing flame from the burner 91 which may, if desired, be a high-low burner to maintain a constantly burning restricted pilot flame.

In disposing of garbage or other refuse in accordance with the embodiment of the invention illustrated in Figures 6, 7, 8 and 9, the following sequence is followed:

With the damper 81, drying and ignition or firing burners 90, 91, and shield 98 positioned as shown in Figure 6, the cover for the chamber at location 82 is opened and the garbage or other refuse in wet or moist condition is introduced into the chamber 82 into position on the grate 73. With the burner 90 ignited, the heated air passes up through the grate openings 96 and into chamber 82, thereby subjecting the wet or moist refuse to a drying or dehydrating stage at a relatively low temperature, and preferably without direct impingement of the flame 95 on the refuse. The baffle 81 is positioned at this time to close the outlet from the chamber 82 to the flue 80, as shown. The heated air and products of combustion pass up through the chamber 82 and through the openings 28' at the top of the partition 71, 72; also, if desired, around spaces between the outer ends of the partition 71, 72 and the interior of the wall 70, or through other openings in the partition 71, 72, and into the ignition chamber located as shown at 83, and thence out through the open flue outlet of chamber 83 to the flue 80.

The grate openings 99 beneath chamber 83 are substantially closed or covered at this time by the shield 98. This prevents appreciable, or at least objectionable by-passing of the heated air through the firing chamber 83, and compels the air for drying or dehydrating and for ignition to pass first through the chamber in which drying or dehydrating of the refuse is taking place, then into the ignition or firing chamber, and thence out through the flue.

Upon completion of the drying or dehydrating stage of the process the handle 100 is grasped and turned about 180° to turn the shaft 71, damper 81, shield 98, and drying and firing burners 90, 91 to positions diametrically opposite the positions shown in Figure 1. The chamber at the location 82 now serves as the ignition or firing chamber, and the flash valve or other flash means is operated to flash or project the flame of the pilot burner 91. This flame impinges through the openings in the grate 73 on the dried or dehydrated mass of refuse to burn and dispose of same without objectionable smoke or odors.

While the dried or dehydrated refuse is burning in the chamber at location 82, damp or wet garbage may be introduced into the other chamber at location 83. Then, upon completion of the burning of the dried or dehydrated refuse in one chamber and drying or dehydrating of the refuse in the other chamber, the handle 100 is manipulated to return the parts, for example, to the positions illustrated in Figure 2, whereupon the burner 91 is operated to burn and thereby dispose of the dried or dehydrated refuse in the chamber at location 83, and the damp or wet garbage or other refuse may be introduced into the other chamber.

It is to be understood that the embodiments of the invention shown in the drawings are for illustrative purposes only, and it is to be expressly understood that the drawings and the accompanying specification are not to be construed as a definition of the limits or scope of the invention, reference being had to the appended claims for that purpose.

I claim:

1. In an incinerator of the class described, in combination, a generally horizontal hearth plate, a generally upright wall surrounding the hearth plate and defining an incinerator space above the hearth plate and a burner compartment beneath the hearth plate, a partition structure extending upwardly from said hearth plate and dividing the space above the hearth plate into a pair of incinerator chambers, said hearth plate having aperture means opening upwardly therethrough from said burner compartment into each of said incinerator chambers, a burner structure disposed in said burner compartment beneath said hearth plate and comprising a drying burner positioned beneath one of said incinerator chambers and an ignition burner positioned beneath the other incinerator chamber, a shield overlying the drying burner to prevent access of the flame of the drying burner to the interior of the overlying incinerator chamber through the aperture means in the part of the hearth plate overlying the drying burner, said ignition burner providing an ignition flame having access to the interior of the overlying incinerator chamber through the aperture means in the part of the hearth plate overlying the ignition burner, and means mounting one of the partition and burner structures for turning movement relative to the other structure whereby to position each one of the incinerator chambers alternately above said drying and ignition burners, with the other incinerator chamber alternately above the other of said burners.

2. An incinerator according to claim 1 wherein the partition structure extending upwardly from the hearth plate and dividing the space above the hearth plate into a pair of incinerator chambers is mounted for turning movement about a vertical axis above the hearth plate, and wherein

the drying burner and ignition burner are mounted in relatively fixed position.

3. An incinerator according to claim 1 wherein the aperture means in the part of the hearth plate overlying the ignition burner is more restricted than the aperture means in the part of the hearth plate overlying the drying burner.

4. An incinerator according to claim 1 wherein the incinerator has a top wall having a flue opening outwardly from the top of the incinerator chamber overlying the ignition burner, and wherein the partition structure has an opening at the top thereof placing the top of the incinerator chamber overlying the drying burner in communication with the top of the incinerator chamber overlying the ignition burner.

5. An incinerator according to claim 1 wherein the partition structure carries walls disposed within the generally upright wall of the incinerator and with said partition structure defining the respective incinerator chambers, and wherein the walls carried by said partition structure are open at the tops and bottoms of the incinerator chambers.

6. An incinerator according to claim 1 wherein the interior of the generally upright wall of the incinerator has inwardly projecting tearing means for pulling the refuse in the incinerator apart as the refuse is moved from drying position to ignition position by turning said partition structure about its axis.

7. In an incinerator of the class described, in combination, a generally horizontal hearth plate, a generally upright wall surrounding the hearth plate and defining an incinerator space above the hearth plate and a burner compartment beneath the hearth plate, a partition structure extending upwardly from said hearth plate and dividing the space above the hearth plate into a pair of incinerator chambers, said hearth plate having aperture means opening upwardly through said hearth plate from said burner compartment into each of said incinerator chambers, a burner structure disposed in said burner compartment beneath said hearth plate and comprising a drying burner positioned beneath one of said incinerator chambers and an ignition burner positioned beneath the other incinerator chamber, a shield overlying the drying burner to prevent access of the flame of the drying burner to the interior of the overlying incinerator chamber through the aperture means in the part of the hearth plate overlying the drying burner, said ignition burner providing an ignition flame having access to the interior of the overlying incinerator chamber through the aperture means in the part of the hearth plate overlying the ignition burner, and means mounting one of the partition and burner structures for turning movement relative to the other structure whereby to position each one of the incinerator chambers alternately above said drying and ignition burners, with the other incinerator chamber alternately above the other of said burners, the aperture means in the part of the hearth plate overlying the ignition burner being more restricted than the aperture means in the part of the hearth plate overlying the drying burner.

8. In an incinerator of the class described, in combination, a generally horizontal hearth plate, a generally upright wall surrounding the hearth plate and defining an incinerator space above the hearth plate and a burner compartment beneath the hearth plate, a partition structure extending upwardly from said hearth plate and

11

dividing the space above the hearth plate into a pair of incinerator chambers, said hearth plate having aperture means opening upwardly through said hearth plate from said burner compartment into each of said incinerator chambers, a burner structure disposed in said burner compartment beneath said hearth plate and comprising a drying burner positioned beneath one of said incinerator chambers and an ignition burner positioned beneath the other incinerator chamber, a shield overlying the drying burner to prevent access of the flame of the drying burner to the interior of the overlying incinerator chamber through the aperture means in the part of the hearth plate overlying the drying burner, said ignition burner providing an ignition flame having access to the interior of the overlying incinerator chamber through the aperture means in the part of the hearth plate overlying the ignition burner, means mounting one of the partition and burner structures for turning movement relative to the other structure whereby to position each one of the incinerator chambers alternately above said drying and ignition burners with the other incinerator chamber alternately above the other of said burners, the partition structure extending upwardly from the hearth plate and dividing the space above the hearth plate into a pair of incinerator chambers being mounted in relatively fixed position and the drying burner and ignition burner being mounted for turning movement as a unit about a vertical axis.

9. An incinerator according to claim 8 wherein in the vertical axis of turning movement of said drying and ignition burners comprises a vertical shaft projecting upwardly above the partition structure, and wherein there is a flue opening upwardly from the top of both said in-

12

cinerator chambers, and a damper fixed to turn with said shaft alternately to close communication between the respective incinerator chambers and said flue.

- 5 10. An incinerator according to claim 8 wherein there is a shield mounted to turn with said drying and ignition burners, and wherein said shield has an opening for registration with said ignition burner and with an aperture in the part 10 of the hearth plate overlying said ignition burner, and wherein said shield is imperforate outwardly of the aperture therein to restrict the aperture means in the part of the hearth plate overlying said ignition burner.
- 15 11. An incinerator according to claim 8 wherein there are spuds at the axis of turning movement of said drying and ignition burners for delivering fuel into the respective burners.

JAMES G. AMES.
